WINDOW CORNICE

Kenneth R. Bixby, 485 E. Losey St., Galesburg, Ill.
Filed Aug. 26, 1958, Ser. No. 757,354
10 Claims. (Cl. 160—39)

The present invention relates generally to window cornices and the like and is more particularly concerned with such devices wherein means is provided to receive decorative covering material.

The object and general nature of this invention is the provision of a decorative window cornice having means assuring that the cover material may be maintained taut and neat appearing at all times, yet may readily be removed for cleaning, replacement and the like.

Another important feature of this invention is the provision of a window cornice structure wherein means is provided for the accommodation of a top closure plate or dust stop or of a plate type support for an associated indirect lighting lamp and associated appurtenances. Another feature is the provision of a lamp support that is adjustable and so arranged that it can be placed with the lamp directing light upwardly or downwardly, as desired.

These and other objects and advantages of this invention will be apparent to those skilled in the art after a consideration of the following detailed description of the preferred structural embodiment, taken in conjunction with the accompanying drawings, in which:

FIG. 1 is a perspective view taken from the window side of the cornice.

FIG. 2 is an enlarged fragmentary perspective view showing the interconnection between the main and end members of the window cornice.

FIG. 3 is a section taken along the line 3—3 of FIG. 1, illustrating the way in which the decorative covering material is fastened to the main member of the cornice of this invention.

FIG. 4 is a fragmentary section, similar to FIG. 3, showing the cover secured in taut relation.

FIG. 5 is a view of the bracket support.

FIG. 6 is a perspective view of one of the cover securing clips.

FIG. 7 is a perspective view of a modified form of dust stop plate or lamp support, the same being adjustable in length.

FIG. 8 is a section showing a modified form of bracket, with a lamp supported on the underside of the support plate.

FIG. 9 is similar to FIG. 8, showing the plate in a lower position with the lamp directing light upwardly.

Referring first to FIG. 1, the cornice of this invention comprises supporting structure that includes a main section 10 made up of three telescoping parts 11, 12 and 13, and end sections 15. The main section 12 is in the form of a sheet metal member having a flat vertical face 21 with an upper marginal section 22 that includes a downwardly and inwardly angled portion 23 and a lower marginal section 24.

The upper marginal section 22 also includes a generally flat inner portion 25, and the lower marginal section 24 includes an upturned edge 26 and a flat portion 27. The associated portions 12 and 13 are of the same construction and hence the same reference numerals have been applied. It will be noted that the intermediate portion 12 is slightly smaller in vertical dimension so that the outer sections 11 and 13 embrace the ends of the center section 12. If desired, the end sections may be arranged within the center section. The sections 11, 12 and 13 may be considered as a main member to the ends of which are connected the end members 15. The downwardly and inwardly angled portion 23

2

is joined to the upper edge of the outer face 21 by a small horizontal portion 28.

The end sections 15, only one of which is shown in FIG. 2, are made substantially like the main member 10 and the corresponding parts are indicated by the same reference numerals that are employed in FIG. 2 but with the suffix *a* added. At the point of juncture between the main and end members, the downwardly and inwardly angled portions 23 and 23*a* are beveled or angled, as indicated at 23*b*, so that when the main and end members are assembled, there is sufficient space *s* between the adjacent end of the horizontal portion 27 and a flange 29 on the outer end of section 13 to receive the forward or outer end of the associated end member 15, as will be clear from FIG. 2. When so connected, the flat sections 25 and 25*a* overlap and are apertured to receive a fastener, such as a sheet metal screw 31. Also, when the parts 12 and 15 are assembled the lower marginal portion 24*a* of end member 15 overlaps the section 24 of member 12, the edge portion 26 thereof being cut off, as at 32, to provide for these overlapping portions. The latter are apertured to receive fastener means in the form of a sheet metal screw 33.

The inner or rear portions of the end members 15 have an inwardly turned flange 36 that carries one or more keyhole slots 37 that are adapted to receive screws by which the end members may be secured to an adjacent wall or window casing W (FIG. 5). To reinforce the above wall connection I provide one or more supporting brackets 40, best shown in FIG. 5. The bracket 40 includes an attaching section 41 and a cornice-receiving section 42. The section 41 is in the form of an angle having a plurality of openings to receiving fastening screws 43 or the like, by which the bracket 45 may be fixed to the wall W. The upper leg of the section 41 is slotted and receives a bolt 45 that extends through a similar slotted portion of the valance receiving section 42. The latter is also generally of angle configuration but in the upper slotted portion 46 is formed an angled section 47 that conforms to the portion 23, 25, 28 of the member 12, whereby the bracket portion 47 securely supports the cornice in the proper position, this action being augmented by a depending bracket portion 48. The position of the bracket 40 is shown in dotted lines in FIG. 2.

The cornice structure of this invention is particularly adapted to receive a decorative cover 50 that may be any suitable fabric or other flexible material. Also, to give the material 50 a padded effect I use a suitable cushion of foam rubber 51 that has inherent resilient compressibility, making use of this characteristic to easily and conveniently secure the cover 50 in position.

Referring first to FIG. 3, the lower edge 53 of the cover 50 is turned back over the lower upstanding edge 26 and then spring clips 54 are applied so as to firmly grip the material and hold it in place, the clips 54 being so constructed and arranged that the wing portions 55 and 56 are biased for gripping action. The clips 54 have projections 58 that enables the operator to secure a better grip on the clips for inserting or removing them, as required. Other clips may be used, such as clips made of plastic, for example.

After the cover has been attached to the lower edge 26 it is then brought upwardly around the foam rubber pad 51 and the upper portion of the cover is then passed over the upper marginal portions 23 and 25, in the manner illustrated in FIG. 3, and the edge of the cover is then folded over the edge of the flat section 25 and brought under the latter. Clips 54 are then applied. The attachment of the cover is completed by pressing the clips 54 toward the angled section 23, which has the result of tightening the cover as the upper portion is

brought down to the position shown in FIG. 4. In thus tightening the cover 50 the foam rubber pad or cushion 51 is compressed, whereby the resiliency of the pad 51 acts to maintain the cover in taut condition. By removing the clips 54 it is a simple matter to remove the cover 50, as for cleaning, replacement or the like.

The flat sections 25 and 25a provide a very convenient support for a plate P, FIG. 1, that is dimensioned to fit snugly between the angled sections 23, 23a and the adjacent wall or other support, resting on the flat sections 25 and 25a. The plate P may be used simply as a dust stop or cover, or it may be used as a support for an indirect lighting unit 60 that may be of any convenient form, such as one or more fluorescent tubes with associated starters, switches and the like.

Ordinarily, the cover material 50 is brought around the end members 15 and fastened to the edges of the flange 36 and the edges 26a but the foam rubber pad is cut so as to stop at the flange 36, so that the end members may be connected to the associated wall or other support by fasteners that extend through the keyhole slots 37 and through only the material 50, not the foam rubber pad.

In FIG. 1 the plate P is shown as a single piece, and therefore it must be cut to fit after the cornice has been adjusted, as shown in FIG. 1. However, as a modified form of this invention, I have shown an adjustable plate P¹ in FIG. 7. The plate P¹ is shown by way of illustration as made up of a pair of sections 61 and 62, each having edge flanges 63 and 64 angled as shown. The part 62 is dimensioned so as to fit telescopically within the other part 61 in slidable relation.

FIGS. 8 and 9 show a modified form of bracket structure. Referring first to FIG. 8, the bracket 66 comprises an attaching section 67 having a short horizontal upper leg 68 and a longer lower leg 69 that is slotted to receive an adjusting bolt 71. The bracket 66 also includes a cornice-receiving section 72 that is provided with a longer lower leg 74 which is slotted to receive the adjusting bolt 71. The legs 69 and 74 normally overlap and are fixed in a position of adjustment by the bolt 71. The cornice-receiving section 72 also includes a relatively short upper leg 76 that is joined to the vertical portion of the section 72 by an upwardly angled part 77 that serves the same purpose as the section 47 described above.

The plate P¹ may serve as a simple dust stop if desired, but it may also be used to support a lamp 80. As shown in FIG. 8, the lamp is disposable in a position between the short legs 68 and 76 being passed between these parts when the plate P¹ is applied to the supporting brackets at their upper portions, between the angled portion 77 and the wall W. In this position light from the lamp 80 is directed downwardly onto the window drapes or curtains. As shown in FIG. 9, the plate P¹ may rest on the lower legs 69 and 74, which disposes the lamp 80 in a position to direct light upwardly. In this case the flanges 63 and 64 are at the lower side of the plate P¹ so that the latter clears the bolts 71. The lamp 80 is conventional and may readily be attached to either side of the plate P¹.

Having described my invention, what I claim and desire to secure by Letters Patent is:

1. A window cornice comprising a sheet metal member having a generally flat outer face and upper and lower marginal sections, each extending laterally inwardly of said member, the lower marginal section having an upturned edge generally parallel to and extending upwardly in generally parallel relation with respect to the main body of said member, the upper marginal section having a downwardly and inwardly angled portion terminating in an inner substantially flat portion, a flexible decorative cover engaged over said upturned edge and extending across said outer face and across said downwardly and inwardly angled portion and then around

and in contact with both faces of said inner flat portion, and cover tensioning means comprising one or more parts having a pair of flat wing portions embracing said inner flat portions and biased to move toward each other so as to press portions of said cover toward both faces of said inner flat portion, movement of said cover tensioning parts toward the juncture of said downwardly and inwardly angled portion and said flat portion serving to stretch said cover while the marginal portions of the same are held against both faces of said flat portions.

2. A window cornice comprising a sheet metal member having an outer face and upper and lower marginal sections, the lower having an upturned portion and the upper having an inwardly and downwardly angled portion terminating in a substantially flat portion disposed generally perpendicular to the plane of said outer face, a flexible cover extending over said outer face and over the edges of said marginal sections, means fixing the lower edge of said cover to said lower upturned portion, and a plurality of generally flat spring clips passed over the inner edge of said flat portion and gripping the edge of the cover at upper and lower sides of said flat portion, said clips being dimensioned so that, when applied over the edge of said flat portion, the clips extend to the juncture of said inwardly and downwardly angled portion with said flat portion, thus stretching said flexible cover over said outer face.

3. The invention set forth in claim 2, further characterized by said spring clips being dimensioned so that when they are forced onto the flat portion with the cover held thereby against the upper and lower sides of said flat portion, the clips force said cover close to the juncture of said flat and angled portions and in doing so serve to tension said cover and cause it to snugly engage said member.

4. In a window cornice construction, a bracket means comprising an attaching section having a short upper leg and a longer lower leg that is slotted, and a cornice-receiving section having an upper relatively short upper leg and a longer lower leg, said longer lower legs being adapted to be fixed together in adjusted position, adjusting means for so fixing said lower legs together, a plate carried by said shorter legs and having edge flanges extending outwardly from one face of the plate, the other face being flat, and a lamp carried by said plate and extending from the flat face thereof in a position to be disposed between said shorter legs, said plate and lamp being invertible so that the plate flanges may be disposed on the lower legs and span said adjusting means.

5. In a window cornice construction, a supporting bracket including an attaching section having a relatively short upper leg and a relatively long lower leg, a cornice-receiving bracket having a relatively short upper leg and a relatively longer lower leg disposed in overlapping relation with said first mentioned lower leg, said lower legs being slotted, and an adjusting fastener extending through said slotted portions, the adjacent ends of said shorter legs being spaced apart, a supporting plate carried on said upper shorter legs, and a lamp unit carried by said plate and disposed between said short upper legs.

6. In a window cornice construction, a supporting bracket including an attaching section having a relatively short upper leg and a relatively long lower leg, a cornice-receiving bracket having a relatively short upper leg and a relatively longer lower leg disposed in overlapping relation with said first mentioned lower leg, said lower legs being slotted, and an adjusting fastener extending through said slotted portions, the adjacent ends of said shorter legs being spaced apart, a supporting plate carried on said lower longer legs, and a lamp unit carried by said plate on the upper side thereof.

7. The invention set forth in claim 6, further characterized by said plate having flanges engageable with

said longer legs on opposite sides of said fastener so as to dispose said plate in a position clearing said fastener.

8. A window cornice comprising a sheet metal member having an outer face and upper and lower marginal sections, the upper marginal section having an inwardly and downwardly angled portion terminating in a substantially flat portion disposed generally perpendicular to the plane of said outer face, a flexible cover extending over said outer face and over the edges of said marginal sections, means fixing the lower edges of said cover to said lower marginal section, and a plurality of flat spring clips passed over the inner edge of said flat portion and gripping the edge of the cover at upper and lower sides of said flat portion, said clips being dimensioned so that, when applied over the edge of said flat portion, the clips extend to the juncture of said inwardly and downwardly angled portion with said flat portion, thus stretching said flexible cover over said outer face.

9. A window cornice comprising a member having a generally flat face and upper and lower marginal sections, each extending laterally inwardly of said member and the lower marginal section having an upturned edge, the upper marginal section having a downwardly and inwardly angled portion terminating in an inner substantially flat portion, a flexible cover engaged over said upturned edge and extending across said outer face and across said downwardly and inwardly angled portion and then around and in contact with both faces of said inner flat portion, and cover tensioning means comprising one or more parts having a pair of wing sections embracing said inner flat portions and biased to move toward one another so as to press portions of said cover against both faces of said inner flat portion, movement of said cover tensioning parts toward the juncture of said downwardly and inwardly angled portion and said flat portion serving to stretch said cover while the marginal portions of the cover are held against both faces of said flat portions.

10. A window cornice having a main section and end

sections, each section comprising a sheet member having a generally flat outer face and upper and lower marginal sections, each upper and lower marginal section on each of said main and end sections extending laterally inwardly of the associated section, each lower marginal section having an edge, the upper marginal section of each of said main and end sections having a downwardly and inwardly angled portion terminating in an inner substantially flat portion, a flexible decorative cover over the edges of said lower marginal sections and extending across the outer face and across the downwardly and inwardly angled portion and then around and in contact with both faces of the inner flat portion of each of said main and end sections, said decorative cover embracing both said main section and said end sections, cover attaching means comprising means attaching the lower portion of said decorative cover to the lower edges of the main and end sections, and cover tensioning means comprising one or more parts having a pair of flat wing portions biased to move toward each other so as to press portions of said cover toward both faces of said inner flat portions of said main and end sections, movement of said cover tensioning parts toward the juncture of said downwardly and inwardly angled portion and said flat portion of each of said main and end sections serving to stretch said cover while the upper marginal portions of the cover are held against both faces of said flat portions.
